Primary Examiner — George D. Kirschbaum*Assistant Examiner* — Suzanne E Tisdell(74) *Attorney, Agent, or Firm* — Winthrop & Weinstine, P.A.; Nadeem W. Schwen; Alicia Griffin Mills(57) **CLAIM**

The ornamental design for a solar power plant, as shown and described.

DESCRIPTION

FIG. 1 is an upper front isometric view of our new ornamental design for a solar power plant in accordance with the present disclosure;

FIG. 2 is an upper right isometric view thereof;

FIG. 3 is a front side elevational view thereof;

FIG. 4 is a back side elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 7 is a front upper left isometric view thereof;

FIG. 8 is a front upper right isometric view thereof;

FIG. 9 is a rear lower left isometric view thereof;

FIG. 10 is a rear lower right isometric view thereof;

FIG. 11 is a front lower left isometric view thereof; and,

FIG. 12 is a front lower right isometric view thereof.

Broken lines included in the drawings show portions of the solar power plant that form no part of the claimed design.

1 Claim, 12 Drawing Sheets(56)
